CONTROL OF HEATING SYSTEMS

Karl W. Rohlin, Merchantville, N. J., assignor to
Warren Webster & Company, Camden, N. J., a
corporation of New Jersey

Application April 22, 1936, Serial No. 75,681

8 Claims. (Cl. 237—67)

This invention relates to heating systems and methods of controlling the same, and more particularly to the controlling of the generation and supplying of the steam from a boiler to a heating system and the returning of the condensate from the system to the boiler.

The invention is particularly adapted for use with relatively small steam heating systems of the class often installed in dwelling houses or other buildings having no cellar, i. e., where the boiler is installed in a position at substantially the same elevation as some of the radiating units. With such installations some form of pumping means or the like is ordinarily provided for elevating or applying a pressure to the condensate returned from the radiating system, to the extent necessary to introduce such condensate into the boiler. The usual practice is to allow an appreciable quantity of such condensate to accumulate in a storage tank where it remains until the quantity is sufficient to operate a float control for starting a motor and pump for pumping the accumulated water into the boiler. With such prior arrangements during the period that condensate is being accumulated in the storage tank, there will be a considerable lowering of the water level within the boiler. Then when the condensate return pump is put in operation and a tank full of accumulated condensate is pumped into the boiler, the water level in the boiler will rise to a somewhat abnormal height. Accordingly with such arrangements there is danger that the boiler water level may at intervals become too low for safety, or if somewhat of an excess of water has been introduced into the boiler, the water may at intervals become too high for efficient generation and distribution of the steam. This invention according to one of its phases provides a method and means for overcoming these difficulties.

Heating systems of the above indicated character are customarily provided with motor driven oil burning apparatus or fuel stoking devices which may be under the control of an indoor or outdoor thermostat, whereby the fuel is fed for firing the boiler at spaced intervals, the intervals being thus regulated thermostatically to meet the heating requirements of the system. As heretofore constructed, such systems have been provided with separate motors for driving the fuel feeding device and the condensate return pump respectively, each of these motors being provided with individual control equipment. However, with the present invention, according to one of its phases, a single motor and a

single thermostatic control may be provided for both the fuel feeding device and the condensate return pump. Thus the invention not only makes possible a substantial saving in the original cost of equipment, but provides in general a greater accuracy of regulation, with the firing of the boiler and the return of the condensate conforming more closely with variations in the heating requirements. The invention also avoids interruptions or delays in the response of the heating system to the thermostatic control.

Various further and more specific objects, features and advantages will clearly appear from the detailed description given below taken in connection with the accompanying drawing forming a part of this specification and illustrating by way of example a preferred embodiment of the invention. The invention consists in such novel features, arrangements, combination of parts and methods as are described in connection with the apparatus herein disclosed by way of example only.

Fig. 1 illustrates a typical form of heating system embodying the invention; and

Fig. 2 is a vertical sectional view showing one example of a condensate return pump adapted for use with the invention.

In Fig. 1 a steam heating boiler is indicated at 10 and to which is connected a steam supply main at 11. A plurality of radiators as at 12, 13 and 14 may be connected to the steam main by steam supply pipes as at 15, 16 and 17 having radiator inlet valves of a well-known form as at 18. The outlets of the radiators may be provided with any suitable well-known form of radiator trap as at 19 through which condensate may pass to condensate return pipes as at 20, thence to a condensate return main as at 21. This return main may be provided with a well-known form of vent trap as at 22. Such a vent trap may for example be provided with a vent opening at a point normally above the water level in the boiler. Such vent, however, is capable of being closed by a float controlled valve whenever the condensate in the return piping exceeds a predetermined level. As shown, the vent of this trap may also be provided with a ball vent valve 23 which is normally closed, but which will permit air or vapor to escape whenever the pressure above the water in the trap exceeds atmospheric pressure by a small amount. And whenever the pressure conditions in the radiating system and return piping are sub-atmospheric, the ball vent valve remains in closed condition whereby a partial vacuum may be maintained in the system.

A condensation pump is indicated at 24 for pumping condensate from the return main through a conduit 25 into the boiler. Check valves 26 and 27 as shown may be provided in the inlet and outlet connections of the pump 24. The pump may be connected to the return main through a lift fitting as at 28 to insure that the pump will have access to the lowest part of the return main and so that water 10 will be available for the intake of the pump, free of air or vapor so long as there is any substantial amount of condensate remaining in the return main.

The boiler may be provided with any suitable 15 well-known type of fuel feeding device 30 such as an oil burner or stoker driven by a motor 31. A source of electric power for the motor is indicated at 32. A thermostat may be provided as at 33 either indoors or outdoors for controlling the operation of the motor 31 in a well-known way through electrical connections as at 34 supplied with current from the power source 32 through a transformer 32'.

The motor 31 may be connected by a shaft 25 35 and resilient connection 36 to a drive shaft 37 for the condensation pump 24. Accordingly, whenever the motor of the fuel feeding device or oil burner is started in operation by the action of the thermostat, the condensation pump will 30 be concurrently started and whenever the thermostat acts to shut off the fuel feeding device, the pump will be stopped at the same time. Thus a single control device and a single motor may be used for both the fuel feeding device and the condensation return pump. Furthermore, both the fuel feeding device and pump 35 will be operated concurrently at spaced intervals with several advantageous results, as will be explained hereinafter.

40 The operation of the system may be described as follows. When the temperature at the thermostat 33 drops, an electrical circuit will be completed through the thermostat, and current from the transformer 32' will serve to actuate any well-known form of control device such as a relay which may be provided at the oil burner for starting the operation of the motor 31 with power from the source 32. Thereupon, fuel is fed into the fire box of the furnace and burned 45 in the usual way. Simultaneously with the starting of the motor 31, the condensation pump 24 will be starting for withdrawing water that has accumulated in the return piping and discharging such water immediately into the boiler, 50 insuring substantially a maximum height of water in the boiler before the boiler is brought up to a temperature causing the generation of steam to begin. Continued operation of the fuel feeding device results in the generation of steam 55 which is quickly condensed in the radiating system. The resulting condensate flows down the return piping to the condensate pump, which continuously returns such water to the boiler during the firing period. When the spaces 60 heated by the system reach a predetermined temperature, the thermostat 33 causes the current to be cut off from the motor 31 which results in stopping the motor and the feeding and burning of fuel in the furnace, as well as 65 currently stopping the return of condensate to the boiler.

70 Thereafter the generation of steam will continue for a period due to the induced vacuum preserved in the system by reason of the fact that the ball vent valve 23 will then be tightly closed.

The condensate resulting during this period, which will be relatively small in amount, accumulates in the return main where it remains until the thermostat again starts the fuel feeding device and condensation pump. However, 5 the loss of the slight quantity of water from the boiler during the period of inaction of the pump is of no consequence, because the oil burner or stoker is then not in operation, so that even a large loss of water from the boiler temporarily 10 during such period would not be harmful.

At the beginning of the next cycle of operation the water stored in the return main is returned to the boiler as above described.

It is apparent that with the above described 15 equipment, it is unnecessary to provide any tank for accumulating the condensate returned from the system, and neither is it necessary to provide any float controlled switch or other equipment such as is necessary with such tanks. The 20 above described equipment not only avoids the necessity of using a separate motor for the condensate pump, but despite the elimination of a tank for accumulating the condensate, it is unnecessary to operate the motor during any larger 25 proportion of the time than such motor is operated for the purpose of driving the fuel feeding equipment. Thus the arrangement is very economical in the use of electric current.

Since this system synchronizes the return of 30 water to the boiler with the generation and discharge of steam from the boiler, it insures that the desired predetermined water level will be steadily maintained in the boiler and at the same time avoiding the injection of large quantities of cold 35 water into the boiler from time to time, which would interrupt the steaming period and interfere with proper thermostatic regulation of the system.

Fig. 2 illustrates a form of condensation return pump particularly adapted for use with the above described system. This pump may comprise a piston 40 reciprocating in a cylinder 41 communicating with the condensate return conduit 25 at a point between the check valves 26 45 and 27. The piston 40 may be operated by a connecting rod 42 which in turn may be pivotally connected as at 43 eccentrically with a worm wheel 44 mounted on a shaft 45. The worm wheel 44 may be driven by a worm gear 46 mounted 50 on the pump shaft 37.

The various parts of the pump may be mounted within a housing 47 as shown, which is designed to contain a body of oil as at 48. An oil settling chamber 49 may be provided within the lower 55 part of the housing 47 communicating through an opening 50 with the main body of oil at 48. The chamber 49 may also communicate through an oil line 51 with a nozzle as at 52 for discharging oil on to the worm gearing and other moving parts. The oil may be caused to flow up through the oil line 51 by pressure created by an oil plunger 53 reciprocating within the opening 50. The plunger 53 may be attached to reciprocate with the pump piston 40 as shown. The 65 worm wheel may be accompanied by a flywheel as at 54 to insure uniform operation of the pump.

Suitable packing of well-known form may be provided as at 55 around the piston 40. Any water which escapes past such packing may be retained 70 within a groove 56 surrounding the upper part of the piston. Such water may be drained off through apertures as at 57 and 58. The upper end of the piston 40 may be provided with a shield 59 for preventing oil from dropping into 75

the water within the groove 56. The chamber 49 may be also connected with the main body of oil 48 through a check valve 60. The oil line 51 may also be provided with a check valve 61.

5 While the invention has been described in detail with respect to particular preferred examples, it will be understood by those skilled in the art after understanding the invention, that various changes and further modifications may be 10 made without departing from the spirit and scope of the invention, and it is intended therefore in the appended claims to cover all such changes and modifications.

What is claimed as new and desired to be secured by Letters Patent is:

1. The method of controlling the generation and supplying of steam from a boiler to a heating system, and returning the condensate from the system to the boiler, which comprises firing 20 the boiler during spaced intervals of time, thermostatically controlling the proportion of elapsed time occupied by such intervals, and forcing substantially all of the condensate returned from the radiating system into the boiler during said 25 intervals of firing.

2. The method of controlling the generation and supplying of steam from a boiler to a heating system, and returning the condensate from the system to the boiler, which comprises firing 30 the boiler during spaced intervals of time, regulating the proportion of elapsed time occupied by such intervals whereby steam is provided substantially in accordance with the system's heating requirements, and forcing substantially all of the 35 condensate returned from the system into the boiler during said intervals of firing.

3. The method of controlling the generation and supplying of steam from a boiler to a heating system, and returning the condensate from the system to the boiler, which comprises firing the 40 boiler during spaced intervals of time, regulating the proportion of elapsed time occupied by such intervals whereby steam is provided substantially in accordance with the system's heating requirements, forcing substantially all of the condensate returned from the system into the boiler during 45 said intervals of firing, and maintaining a sub-atmospheric pressure in the system during a substantial part of the time between said intervals.

4. The method of controlling the generation and supplying of steam from a boiler to a heating system, and returning the condensate from the system to the boiler, which comprises firing 50 the boiler during thermostatically controlled spaced intervals of time, permitting the condensate to return by gravity and accumulate at a low point in the system during times between intervals of firing, and forcing such accumulated 55 condensate into the boiler during spaced intervals, the intervals of firing and the intervals of forcing the condensate into the boiler being initiated substantially concurrently.

5. The method of controlling the generation and supplying of steam from a boiler to a heating system, and returning the condensate from the system to the boiler, which comprises firing 60 the boiler during thermostatically controlled spaced intervals of time, permitting the condensate to return by gravity and accumulate at a low point in the system during times between intervals of firing, also permitting a subatmospheric pressure to be induced in the system during 65 said intervals.

times, and forcing such accumulated condensate into the boiler during spaced intervals, the intervals of firing and the intervals of forcing the condensate into the boiler being initiated substantially concurrently.

5

6. The method of controlling the generation and supplying of steam from a boiler to a heating system, and returning the condensate from the system to the boiler, which comprises firing the boiler during thermostatically controlled 10 spaced intervals of time, permitting the condensate to return by gravity and accumulate at a low point in the system during times between intervals of firing, and introducing such accumulated condensate into the boiler during spaced 15 intervals, and causing each of said last named intervals to occur substantially during an interval of firing.

7. A steam heating system comprising radiators, a boiler, steam supply conduits for connecting said boiler to the radiators, return conduits for conveying condensate from the radiators to a point in the system below the normal water line in said boiler, means in said return conduits to prevent passage of steam there- 20 through, a pump for forcing the condensate from said point into the boiler, a fuel feeding device for the boiler, means for starting and stopping said fuel feeding device at intervals depending upon the heating requirements of the system, said means also being operatively associated with said pump whereby said pump operates to return condensate to the boiler only during intervals which occur substantially during intervals of firing, and means for discharging air from said 25 return conduits at times when a substantial fluid pressure exists at said point in the system, whereby during non-firing intervals subatmospheric pressure conditions are promoted in the boiler and steam supply conduits, with consequent 30 35 prolongation of the intervals of steam supply.

8. A steam heating system comprising a plurality of radiating units, a steam boiler, steam supply conduits connecting said boiler to the radiators, a return conduit system for conveying 40 condensate from the radiators to a low point in the system below the water line in said boiler, means in said return conduits to prevent passage of steam therethrough from the radiators, a fuel feeding device for the boiler, means for operating 45 said device during periods alternating with intervals of non-firing, the relative duration of said intervals and periods depending upon the heating requirements of the system, the return conduit system having sufficient capacity at and 50 adjacent said low point to receive and retain the condensate returned during each of said intervals, a pump for forcing the condensate from said low point into the boiler, said last named means also being operatively associated with said 55 pump whereby said pump operates to return condensate to the boiler only during periods which occur substantially during said firing periods, said boiler having a water capacity in relation to the remainder of the system, such as to 60 store sufficient heat during each firing period, to continue supplying substantial quantities of steam after termination of each firing period, and yet retain the boiler water level within a normal and narrow predetermined range during 65 70 each of said periods and intervals.
